[57] CLAIM

The ornamental design for a solid block wash chemical designed with regular curved and linear aspect, as shown and described.

DESCRIPTION

FIG. 1 is a perspective view of the solid block wash chemical designed with regular curved and linear aspect of the present invention;

FIG. 2 is a top plan of the solid block wash chemical designed with regular curved and linear aspect of the present invention;

FIG. 3 is a bottom plan of the solid block wash chemical designed with regular curved and linear aspect of the present invention;

FIG. 4 is a side elevation of the solid block wash chemical designed with regular curved and linear aspect of the present invention; and,

FIG. 5 is a front elevation of the solid block wash chemical designed with regular curved and linear aspect of the present invention.
